SHEET PULP CONTAINER FORMING APPARATUS

Lee M. Wiley, Marion, Ind., assignor of one-third to Julian T. Lett and one-third to Reeley B. Wiley, both of Marion, Ind.

Application May 27, 1942, Serial No. 444,671

6 Claims. (Cl. 18—4)

This invention relates to the substantial dehydration and final formation of deep seamless containers formed from flat fibrous sheet stock suitably damped and/or impregnated, coated or the like.

The chief object of this invention is to reduce the number of finishing operations and operating time over that initially and broadly disclosed in copending application Serial No. 288,343, filed August 4, 1939, entitled, "Sheet pulp container forming process and apparatus therefor," and now matured into Patent 2,337,581, dated December 28, 1943.

As disclosed in said patent, paper sheet stock is subjected to moisture and other liquid materials, then blanked to the required size and shape, then precreased or fluted in blank ejection to a receiver mold and then initially molded. A modified form of blanking, precreasing and pre-forming in a receiver mold is also disclosed in the copending application Serial No. 334,823, filed May 13, 1940, and entitled "Process and apparatus for forming seamless fibre stock containers." This partially formed article, formed as aforesaid, from which excess moisture, liquid, et cetera, has been mechanically expressed by pressure, is automatically discharged from the receiver mold to an article support on an endless conveyor having intermittent movement since the receiver mold is turret mounted and indexible from station to station.

For the purposes of this invention this disclosure starts with said endless conveyor. Herein the same passes through a two-stage dryer and then to a stuffer device. Here the articles are supplied to a turret type former and following further formation and treatment therein, they may be discharged to a stacking tube for subsequent packaging.

The chief feature of the present invention resides in the two-stage heater and article travel therein.

Another feature resides in turret type former with its associated article supplying and discharging mechanisms.

Other objects and features of the invention will be set forth more fully hereinafter.

The full nature of the invention will be understood from the accompanying drawings and the following description and claims:

In the drawings,

Fig. 1 is a somewhat diagrammatic elevational side view of the heater, former, and associated mechanisms.

Fig. 2 is a diagrammatic top plan view of the same.

Fig. 3 is a somewhat diagrammatic elevational side view of the transfer and stuffing mechanism 5 between heater and former.

Fig. 4 is a transverse sectional view of the stripper mechanism.

Fig. 5 is an elevational view of a portion of the conveyor structure parts being shown in section.

10 Figs. 6 and 7 are central section and end elevational views, respectively, of the parts shown in Fig. 5.

As initially stated herein, the blank stock prior to blanking has been subjected to conditioning that is the application of moisture, et cetera. The resulting blank is then creased or fluted in a predetermined manner prior to reception by a receiver mold in which a large percentage of the moisture (free moisture) is pressure extruded, et cetera. The conveyor mentioned, to which the receiver molds discharge partially formed articles in oven entering run indicated by the numeral 10 in Fig. 1.

As distinguished from the prior copending disclosures, the upper run 10 of the conveyor enters the oven 11 through opening 12. This run then passes to sprocket 13 and then back and forth over sprockets 14 and 15 gradually rising in the oven.

30 The oven includes a baffle plate 16 that terminates at 17 so that run 18 lies above said baffle. Sprocket 19 above the plate 16 directs the conveyor to sprocket 20 above another and offset baffle 21. Baffle 16 forms a lower and dehydrating chamber 22 which in the present instance, contains six runs of the conveyor.

Baffles 21 and 16 form a superposed preheating chamber 23 in which there are approximately three runs of the conveyor. These chambers 40 communicate by throat 24 formed by baffles 16 and 21. The preheating chamber is elongated and overhangs at 23 the dehydrating chamber at the discharge end of the oven, such discharge passage being indicated at 25 in which is mounted 45 sprockets 26. The wall of the dehydrating chamber is extended upwardly at 10a forming a baffle in turn providing throat 27 between the preheating chamber 23 and discharge passage 25.

Near the base of the oven 11 and approximately 50 below sprockets 26 are sprockets 28 adjacent opening 29 opposite opening 12. The lower and return run of the conveyor is indicated by 30 and passes from the oven 11 through opening 12 to the transfer station at the turret type former

having the receiver molds before mentioned and not shown herein. Following article transfer to the conveyor it and said articles enter the oven at 12 as aforesaid.

Preferably conveyor travel is intermittent to permit conveyor and receiver mold registration for article transfer during the turret dwell period during which one set of receiver molds receives and preforms the blank, another set pressure forms same, and another set discharges articles to the conveyor herein all as set forth in the first mentioned copending application.

It is to be understood the conveyor diagrammatically illustrated in Fig. 1 includes two spaced chains of sprocket link type suitably connected together at predetermined distances apart by transverse members 31—see Fig. 2—central part.

Referring now to Figs. 5 to 7, it will be noted member 31 is tubular and spaced along the same are mushroom-like article supports having the head 32 and stem 33 rigid therewith. As shown in Figs. 6 and 7, tube 31 is non-circular and a support base 34 is adjustably but rigidly mounted on the tube by cap 35. A shank 36 is socketed at 37 to receive the lower end 33b of stem 33 shouldered at 33a. The socket is split at 37a and clamp bolt 37b rigidly secures the stem 33 in said socket.

It will be appreciated that support 32—39 can be readily removed and replaced by another support whenever another type of article is fabricated. This is effected by loosening 37b. Also, it will be understood that by removing cap 35, the entire individual support can readily be removed without disturbing other supports or the conveyor. By loosening the caps 35 the supports on tube 31 can be readily adjusted thereon as desired or required with regard to spacing between supports in transverse alignment.

The immediate connection of the ends of tubular member 31 to chains 18 is shown in Figs. 5 and 7. Herein the tubular element 38 has a center which is the center of a roller chain link. Mounted thereon is ball race 39 and mounted thereon is socket 40 having depending portion 41 which at its lower end is notched, or bifurcated as at 42 to nest or seat the adjacent end of tube 31. A bolt 43 extends through registering apertures 31a in the seated end of the tube and is threaded into portion 41 at 43, portion 41 being relieved or recessed at 41a for bolt end reception.

From the foregoing it is noted that all mushroom supports, of which there are seven, with the cross member 31 and end members 41 are one rigid unit which swivels about the center of spaced members 38 of the sprocket chain conveyor 18 and upon races 39.

The comparative weights are such that the parts always assume a position, when not positively constrained, such that heads 32 are always uppermost. This means the articles nested thereon always are retained on the supports in conveyor travel from the receiver mold transfer station to and through the oven and at the discharge end thereof. Certain of the sprockets are power driven and certain are of idler type. Operation of the conveyor, as stated, is preferably of intermittent character.

Reference will now be had more particularly to Figs. 1 and 2 for a disclosure of the oven construction, control and operation. Access to the interior of the oven, which is required for sprocket, chain, et cetera inspection, repair and lubrication may be provided by suitable means wherever necessary or convenient. Same, how-

ever, for clearness are not herein illustrated. The oven likewise should be of insulated character but such heat insulation is similarly not illustrated for like reasons.

In Fig. 1 there is illustrated a plurality of heat supply ports 44 in the dehydrating chamber 22. Herein two are illustrated. The numeral 45 indicates a plurality of exhaust ports and of like number. In the preheating chamber 23 a plurality of heat supply ports 46 are provided. Herein two are shown.

For convenience the oven heat is supplied by air heated externally of the oven 47 indicating electric heat supply means for the air in unit 48.

The air heated in unit 48 is drawn from same by fan 49 and supplied to conduits 50 which connect to the supply ports 44 and 46. The fan draws this air through unit 48 from conduits 51 connecting at one end to unit 48 and at the opposite end to the discharge ports 45. Thus recirculation is effected thereby reducing heat cost to a minimum.

For a better understanding of the foregoing portion of the invention, the following is set forth by way of example only and same is illustrative and not restrictive in character.

In this example if all mushroom supports are covered, there will be 819 in the dehydrating chamber and 427 in the preheating chamber at any one time. The respective temperatures found satisfactory are 250° to 350° F. in the dehydrating chamber and 400° to 500° F. in the preheating chamber. Controls, not illustrated, maintain chamber temperatures within a 15° range of the predetermined desired temperature.

The conveyor 18 is endless and approximately 130 feet in length of which approximately 99 feet are in the oven at all times. A satisfactory conveyor speed is twelve and a half feet per minute. For six inches of conveyor travel an interval of one and two tenths seconds is required. This interval is then followed by a like pause interval so that the chain advances the aforesaid distance of six inches every two and four tenths seconds of operation. Since 99 feet of the conveyor are in the oven and the aforesaid speed and travel prevails in the selected example, each article is in the oven approximately 198 intervals of 2.4 seconds or slightly less than eight minutes and of this approximately 5.8 minutes is period in the dehydrating chamber portion.

By test of one article example, including water and ethyl acetate, the article when entering the oven weighed 32.6 grams, of which 16.3 grams were pulp fibre, 4.4 grams of solids (including resins, sizes, et cetera), 11.0 grams of water and 0.9 gram of ethyl acetate. Such article leaving the oven weighed 22.28 grams so since substantially all the acetate and most of the water is removed in the dehydrating chamber 10.23 grams of water and 0.9 gram are acetate are so removed. Practically none is removed in the preheating chamber which is for conditioning the water soluble and/or emulsifiable thermoplastic resins et cetera, for subsequent treatment in finishing operation. The article when finished weighs but 20.7 grams so that in that final operation 0.73 gram of water are pressed and steamed out as hereinafter described. This 0.73 gram plus 10.23 grams totals 11.0 grams so the resulting article is substantially devoid of moisture as well as ethyl acetate.

The term residual moisture is applied to the 0.73 gram content. In the oven the 819 articles initially weigh 59 pounds. In the 5.8 minutes

required to travel through the dehydrator approximately 18.5 pounds of water are lost as well as one and a quarter pounds of ethyl acetate or a loss of 19.75 pounds.

In the preheating chamber the 427 articles weigh 21 pounds. The total weight of the 1,246 articles in the oven at any one time may be said to be 39.25 pounds plus 21 pounds plus half the loss of 19.75 pounds or approximately 70 pounds since the dehydrator entering articles are fully saturated and the dehydrator discharging articles are dry except for residual moisture.

Reference will now be had to Figs. 1 and 3, wherein the stuffing transfer or discharge device is illustrated. As shown in Fig. 1 between the vertically aligned, superposed sprockets 26 and 28 and offset relative thereto, are two pairs of spaced sprockets 54 and 56 with an intermediate pair of sprockets 55, only one of each pair being shown. These sprockets are supported by shafts bearing the subscripts *a* on a T-shaped subframe 57a slidably mounted in ways in the spaced frame members 57. These members 57 are carried by the frame 58 of the turret type finishing mechanism having turret 59 rotatably supported at 60 upon a horizontal axis. This turret is four sided and each face detachably mounts a sub-base 61 mounting a number of finishing female molds 62 corresponding to the number of mushroom supports in transverse alignment.

The frame members 57 includes horizontal ways 63 and the subframe 57a is T-shaped and slidably mounted therein. Pivoted on the cross-head portion 64 is connecting rod 65 pivoted at 66 to one arm 67 of a bell crank structure pivoted at 68 and having arm 69 pivotally connected at 70 to a longitudinally adjustable link 71 pivoted at 72 to arm 73 operable by a cam on a shaft 74, see Fig. 2. This shaft is also the power shaft for the stripper mechanism hereinafter to be described.

Shaft 68 extends across the machine and the ways are duplicated so both sides of the T-shaped subframe 57a are caused to move toward and away from the female molds 62 in the actuation of the cross heads 64. Positioned intermediately on the shaft 55a is the equivalent of a star-wheel. It is shown dotted at 75 in Fig. 3 and includes rollers 76 and seating notches 77 therebetween. Now as each tube 31 reaches the star-wheel 75, the tube seats in the seat 77 so that the article support is no longer subject to gravity but is positively tilted as shown in Fig. 3 and in the rotation of the star-wheel.

Contraction of the article in the dehydrating oven insures retention of said article upon the mushroom to which it then clings. To insure exact registration adjacent the star-wheel 75 is a slotted member 78 with slot 79. It is stationary. As the T-shaped members move toward receiving molds 62 a roller 76 enters slot 79 and moves forward therein. This holds the star-wheel and sprocket 55 stationary during article stripping.

When stripping is completed, the aforesaid structure is retracted and roller 76 is free of the slot, etc., and the conveyor can advance one distance unit of travel. Observe from Fig. 1 that the three associated stuffing mechanism pairs of sprockets 54, 55 and 56 constitute a triple reel mechanism and are so positioned relative rollers 26 and 28 that sprocket chain stretching is not required. This is because while sprockets 26 and 28 are in substantial alignment, this alignment is not tangential to aligned sprockets 54 and 56.

The offsetting before mentioned, therefore, permits sprockets 54, 55 and 56 to reciprocate as a unit without chain stretching, as it were.

Reference will now be had to the stripper mechanism which is illustrated rather completely in Fig. 4 and to a certain extent in Fig. 3. In the latter the actual stripper fingers 80 move up and to the right from the full line position to the dotted line position. This movement naturally cannot be completed until the article has been advanced and seated in the receiving female mold 62. Return movement of the stuffing mechanism (in the reciprocation) as previously described, results in the article engaging the stripper finger 80 and being held thereby so that the article clinging connection to the support is broken and the article is retained in receiver 62.

Following this action or simultaneously with the stripper-article engagement a valve 81, see Fig. 3, may be opened to supply suction to the female die 62 from passage 82. This holds the article in the mold until suction is released, to which reference will be had later.

Referring to Fig. 3 note frame 57 is extended downwardly at 83 to support guide plates 84 at 85 as well. Said plates at opposite sides of the machine include two superposed slots 86 in vertical alignment and each terminates in angular upward extension 86a. Shaft 87 is the actuator for the stripping fingers, as hereinafter pointed out. The actuator thereof is arm 93 keyed thereto at 87a and the portion 93b thereof is pivotally connected at 93c to an adjustable link 9 pivotally connected at 9a to a rocker arm 8 mounting a follower 7 riding in slot 6 in a circular internal cam 5 on shaft 74, see Fig. 2. The rocker arm is suitably pivoted at its other end. Note cross-head actuating arm 73 is similarly actuated by a comparable cam on cam shaft 74.

These stripping fingers, see Figs. 3 and 4, are bifurcated at 80c and each is tapered at 80a. The base 80b is detachably secured to cross member 88 by bolt 89 and tongue 80d seating in slot 88a. Cross member 88 mounts spaced shafts 90 carrying rollers 91 riding in the slots 86-86a aforesaid, see Fig. 3. The cross member 88 at each lower end includes a bearing face 88b and a notch 88c. Adjustable stops 92 limit the lower position of member 88.

Shaft 87 aforesaid mounts arms 93 which are pivotally connected by pins 93a to links 94 having the upper ends seated in notches 88c and the lowermost shafts 90 constitute the link pivotal connections to the cross member 88. Accordingly, as shaft 87 is rocked, the cross member 88 with the fingers 80, corresponding to article being fabricated, is raised and lowered and moved laterally in the upper part of its movement by the angular portions 87-86a of slots 86.

From the aforesaid it is apparent that when the horizontally directed article supports (positively constrained as described) are stabilized in the extended position by bodily movement to the right of the entire stuffing or triple reel mechanism, the stripping fingers have moved upwardly and to the right to strip the articles from the mushroom supports and trap the articles in the receiver molds 62, said articles being then retained therein by friction and/or suction as described, which permits the fingers subsequently to retract to inoperative, lowered or idle position. The conveyor 10 then indexes as it were, as well as turret 59 carrying receiver molds 62.

Reference will now be had more particularly to Figs. 1 and 2. Therein is illustrated a turret

type finishing press. As previously suggested, channel 82, see Fig. 3, at the loading station may be subject to suction. However, same is not essential since in the preheating stage, the article if of plasticized character, is slightly tacky on its surfaces. Hence, when applied to receiver mold 62 and stripper 80 holds the article in the mold, the tackiness will cause article retention in the receiver mold following stripper removal and during turret rotation.

As shown in Fig. 4 of Patent No. 2,337,581 aforesaid, a ring or mouth former and a central plunger slideable therethrough, although herein duplicated, are relatively reciprocable toward and away from a female mold containing the semi-formed article. A somewhat similar arrangement is illustrated in Fig. 2 of said patent for the second station operation in a turret type former, a singular male die arrangement at the third station and an article ejector arrangement at the fourth station.

Herein, see Fig. 1, the second station frame portion is indicated by the numeral 95, the third station frame portion by 96 and the base and fourth station frame portion by 97. The loading or first station frame portion is indicated by 51.

At the first finishing station 98 indicates the mouth forming member and 99 the plunger or central male portion of the multiple die. Either or both of these as well as female mold 62 may be electrically heated when desired. As set forth in the last mentioned patent, the outer die member 98 is detachably secured to a cross head slideable in ways carried by frame 95. This cross head provides ways upon which slides a second cross head to which is detachably secured the plunger 99. These two cross heads are each connected to a toggle structure and each toggle structure has its midportion connected to one end of a connecting rod in turn connected at its opposite end to suitable actuating mechanism such as illustrated in Figs. 2 and 4 of Patent No. 2,337,581 or to a crank pin carried by a plate rotatably mounted. Herein at the second station two plates 100 and 101 carry crank pins 102 and 103, respectively, to which are connected rods 104 and 105. These rods are connected as stated, to the toggle structure midportions for die movement toward and away from the receiver female die and relative movement between the male die portions.

At the third station there is provided the aligned male dies and the mouth former is designated by 106 and the central plunger by 107. In like manner these are actuated by connecting rods and toggles through cross heads slideable in ways. Herein 108 and 109 designate plates with pins 110 and 111 with connecting rods 112 and 113, respectively.

The two plates 100 and 101 are carried by shafts mounting meshing gears 114 and 115, respectively. Similarly plates 108 and 109 are mounted on shafts mounting meshing gears 116 and 117. Rigid with the gear 117 mounting shaft is a sprocket with which meshes chain 118 associated with an adjustable tension idler 119. Chain 118 is driven by a sprocket on shaft 120 which also mounts sprocket 121 driven by chain 122 tensioned by idler 123. A gear 124 on shaft 120 meshes with gear 115 for crank rotation. Chain 122 in turn is carried by a lower sprocket (not shown) mounted on a shaft indicated at 125 in Fig. 2.

As shown in said figure a conventional source

of power is the line shaft 126. Power is taken therefrom at 127 by bevel gears to drive member 128 connected by means 129 to mechanism 130 for actuating shaft 131, the shaft upon which is mounted the sprockets 28 in the discharge portion of the oven.

Shaft 14 is extended, see Fig. 2, and mounts sprocket 132 which is chain connected to sprocket 133 suitably associated with a shaft 134, see Fig. 1, that mounts a turret 135 from which projects spindles 136 carrying mushroom supports 137, if desired, similar to those illustrated in Figs. 5 and 6. This turret is indexable in timed relation with turret 59.

When the turrets are stationary, the articles may drop from molds 62 to supports 137 or be blown thereto. At the second station of turret 135 a printing attachment, indicated schematically, may be provided and same is indicated at 138. Same derives ink from transfer roll 139 contact ink feed roll 140 in ink box 141.

At station three of turret 135 a suitable article receiver such as tube 142, may be provided. While much of this description has been in the singular, the same is intended, whenever necessary, to cover seven longitudinally aligned units in each instance.

Certain parts are detachable for repair, replacement, as well as substitution whenever different shaped containers are desired other than those of the bean pot style herein illustrated.

It is also to be understood that final formation of the article occurs in association with turret 59. This final formation, as stated, may be by heated dies. However, it is to be understood that the resins are conditioned in the preheating chamber in oven 11 and may be pressure consolidated only or consolidated by heat and pressure simultaneously and at one or two stations as desired or required. Printing and decorating likewise may be applied or omitted as desired.

Again referring to Fig. 2, note that bevel gears 143 supply power from line shaft 126 to sprocket 144 carried by shaft 145 engaged by chain 146 tensioned as at 147 and driving sprocket 148 on shaft 149. Sprocket 150 also on shaft 149 mounts chain 151, tensioned at 152 and driving sprocket 153 on shaft 154. Spool 155 and drum 156 also are mounted on said shaft and constitute the drive for the turret 59. A clutch 157—158—159 is also provided and from same power is derived by a chain through sprockets, 160 being carried by shaft 128.

Note that ejection from the stuffer, ejection to the printing turret and ejection to the tube 142 all occur while the two turrets and the conveyor are stationary and article forming by dies 98—99 and 106—107 also occurs at this interval.

When the turrets index, the stuffing mechanism is retracted, the strippers are lowered and the conveyor is advanced one step or distance interval.

The invention claimed is:

1. A transfer mechanism for transferring successively presented articles comprising in combination a movable cup-shaped article receiving means, means moving said receiving means to a transfer station and therefrom, an endless conveyor means, article supports carried thereby in spaced relation, said supports being shaped to nest in said receiving means, conveyor operating means, means for bodily moving a portion of the conveyor means towards and away from said transfer station for nesting and denesting respectively an article support in an article re-

ceiving means, stripper means juxtaposed to the transfer station, and means actuating said stripper means in timed relation to the movement of the article support into the receiving means for stripping the article from the support and holding the article in the receiving means during retraction of the article support from said station for effecting article transfer, the conveyor operating means and the means for moving the receiving means being actuatable simultaneously.

2. A mechanism as defined by claim 1 wherein the means for bodily moving a portion of the conveyor includes three alternately and oppositely offset, bodily movable and rotatable structures, two fixed position, spaced rotatable structures between which the three first named structures are positioned, the conveyor means passing about portions of each of said structures, the extreme limits of the movement of the bodily movable structures being at opposite sides of a plane common to the axes of rotation of said two spaced rotatable structures.

3. A mechanism as defined by claim 1 wherein said means for bodily moving a portion of the conveyor means comprises a T-shaped subframe, a supporting frame therefor, a ways and cross-head connection therebetween, and intermittently operable means for actuating the crosshead thereof for subframe reciprocation.

4. A mechanism as defined by claim 1 wherein in each of the article supports is movable relative to the conveyor means and means are provided for normally constraining the supports to a predetermined position, and means juxtaposed to the transfer station for moving the support at said station into a position suitable for nesting the support in the receiving means at said station.

5. A mechanism as defined by claim 1 wherein each of the article supports is movable relative to the conveyor means and means are provided for normally constraining the supports to a predetermined position, and means juxtaposed

to the transfer station for moving the support at said station into a position suitable for nesting the support in the receiving means at said station, said last mentioned means including a pin and slot connection.

6. Apparatus comprising a single, two-stage oven having an intake opening at one end and near the bottom thereof and a discharge opening in the opposite end and near the top thereof, the planes of the openings being substantially transverse to each other, endless conveyor means entering at the intake opening and leaving at the discharge opening and having a plurality of passes within the oven, partition means therein to form successive chambers for dehydration and preheating purposes respectively, article supports carried by the conveyor means for conveying articles through the oven for dehydration and preheating, a transfer device juxtaposed to the discharge opening and comprising a triple reel structure operatively associated with the conveyor means, the latter passing about portions of each of the reels, a plurality of movable article receiving means spaced from the oven, means for moving each of the plurality of receiving means to a transfer station, means for moving the three reels bodily toward and away from the oven and simultaneously away from and toward the transfer station respectively, reel movement toward said station positioning the article support in the receiving means at said station, and stripping means at said station for stripping articles from the supports and retaining the stripped articles in the receiving means when the reel structure is retracted toward the oven, the means moving the receiving means operating only when the reel structure is sufficiently retracted toward the oven for support clearance relative to the receiving means, the conveyor means being advanced only when the reel structure is retracted from the transfer station.

LEE M. WILEY.
